[57] **CLAIM**

The ornamental design for a folding stroller with swiveling front wheel, as shown and described.

DESCRIPTION

FIG. 1 is a perspective view of a folding stroller with swiveling front wheel showing our new design;

FIG. 2 is a right side elevational view;

FIG. 3 is a left side elevational view;

FIG. 4 is a front elevational view;

FIG. 5 is a rear elevational view;

FIG. 6 is a top plan view; and,

FIG. 7 is a bottom plan view.

The broken lines shown in FIGS. 2 and 3 are for illustrative purposes only and form no part of the claimed design.
